UNITED STATES PATENT OFFICE.

ANDREW STENGER, OF CHICAGO, ILLINOIS.

VALVE.

1,179,377.

Specification of Letters Patent. Patented Apr. 11, 1916.

Application filed August 16, 1915. Serial No. 45,718.

To all whom it may concern:

Be it known that I, ANDREW STENGER, a citizen of the United States of America, and a resident of Chicago, county of Cook, and 5 State of Illinois, have invented certain new and useful Improvements in Valves, of which the following is a specification.

Heretofore, needle valves have been made to operate by turning a hand wheel several 10 times until the valve is opened or closed. Valves of this type have been very efficient because they are capable of taking up wear of the valve seat as fast as it occurs, but such valves have the disadvantage of not 15 indicating to an observer whether they are open or closed. Another type of valve in common use is the lever-handle key or plug valve in which the fluid passes through an aperture in the key when the key is turned 20 to bring each end of the aperture into alignment with the openings in the body of the valve. This type of valve has the advantage of being shifted from a fully open position to a completely closed position, or vice versa, 25 by a quarter rotation of the operating handle, said handle being spaced so as to indicate to an observer whether the valve is open or closed. However, these lever-handle key valves have quite a serious defect 30 because of the inability to adjust them when the key or plug becomes worn around its periphery in the middle thereof in such manner that the fluid leaks therearound.

The main objects of this invention are to 35 provide an improved form of valve which embodies the advantages of both the needle valve and the lever-handle key valve; to provide a needle valve adapted to be shifted from one to the other of its limiting positions by turning a lever handle substantially 40 ninety degrees; and to provide improved means for preventing the valve from being accidentally opened and for adjusting the position of the valve stem when the valve 45 is open.

An illustrative embodiment of this invention is shown in the accompanying drawings, in which—

Figure 1 is a sectional elevation of a valve 50 constructed according to this invention, ap-

plied to a supply pipe. Fig. 2 is a section on the line A—A of Fig. 1. Fig. 3 is a bottom plan of Fig. 1. Fig. 4 is a front elevation of the yoke used in connection with the bridge plate.

55

In the construction shown in the drawings, a stem 1, having square double threads 2 of coarse pitch, is threaded into the body 3 of the valve, and is located so that the tapered end 4 will fit on the valve seat 5. 60 Rotation of the valve stem is effected by a handle 6 secured to the octagonal top 7 of the stem by means of a set screw 8. Due to the coarse pitch of the double threads 2, the valve stem might easily become unseated accidentally and leak. Such unseating of the stem is prevented by means of a spring ratchet construction comprising a plurality of ratchet teeth 9 cut in an annular boss 10 formed on the upper part of the 65 body 3, and a plurality of pawls in the form of springs 11 set in the depending flange 12 of a second handle 14, which is slidably mounted on the end 7 of stem 1. The handle 14 is normally urged downward by a compression spring 15 located between the handles 6 and 14, but which may be slid upward on the stem against the action of the spring 15, the space between the 70 handles being sufficient to permit the springs 11 to be raised up above the ratchet teeth 9, thus allowing the stem 1 to be rotated to open the valve. The springs 11 are prevented from slipping out of the recesses in 75 which they are set by an annular ring 16 secured to the lower edge of the depending flange 12 by screws 17. The teeth 9 are beveled on their upper edges at 18 in 80 such manner that the springs 11 are deflected outward and guided into their proper 85 positions when the handle 14 is released after being raised to disengage the springs and 90 teeth.

Means for preventing the valve as a whole 95 from shifting relative to the supply pipe 19, into which it is threaded, when the lever handle is turned from one position to another, are provided and comprise a yoke 20 20 shaped to embrace a reduced portion of the valve body. The yoke 20 is provided with 100

- a threaded stud 21 shaped to pass through an aperture in a bridge plate 22 which bears against and is disposed between the under side of the valve body and supply pipe.
- 5 Tension is secured between the plate 22 and yoke 20 by means of a nut 23 threaded on the stud 21 after the plate has been placed in position.
- The operation of the device is as follows:—The ratchet mechanism is so arranged that the handle 6 may be turned to cause the seating of the valve stem without the lifting of the handle 14, the double threads on the stem being of such pitch 10 that a quarter turn of the handle 6 will shift the valve stem from a fully open position to a completely closed position. When it is desired to open the valve, the two handles 6 and 14 are first grasped and squeezed together, whereby the lower handle 14 is slid upward on the valve stem, disengaging springs 11 from the ratchet teeth 9, and then the handle may be rotated to open the valve to any desired position. When the handle 14 is released, the spring 15 forces it downward, the springs 11 contacting with and being cammed outward by the beveled portions 18 of the shoulders 9.
- The number of teeth on the ratchet may 20 be different from the number of springs, as for example, in the construction shown in Fig. 2, the number of ratchet teeth being 16 and the number of springs being 12. With such an arrangement as this, twelve 25 different adjustments in a ninety degree rotation may be had.
- Before the valve is applied to a supply pipe, the yoke 20 is slipped over the reduced portion thereof and after the valve has been 30 threaded to the pipe, the bridge plate 22 is placed underneath the valve and pipe in position to bear upon the same, and the nut 23 is tightened against said plate, thereby causing tension between the yoke and the 35 valve body sufficient to prevent the valve as a whole from being twisted from its proper position by the turning of the operating handle.
- Although but one specific embodiment of 40 this invention has been herein shown and described, it will be understood that numerous details of the construction shown may be altered or omitted without departing from the spirit of this invention as defined by the following claims.
- I claim:—
1. A valve, comprising a body having a passageway therethrough, a valve stem, a pair of handles on said stem, one of said 45 handles being rigidly mounted and the other being slidably mounted and rotatable in unison with said rigid handle, and ratchet means acting between said body and said shiftable handle for normally preventing
- the shifting of said stem toward one of its 65 limits, said ratchet means being retractable by the shifting of said slidably mounted handle.
2. A valve, comprising a body having a passageway therethrough, a valve seat, a 70 needle valve stem, a lever handle on said stem, connections between said body and stem for seating and unseating said stem by a substantially ninety degree rotation of said handle, a plurality of ratchet teeth 75 on said body, a second handle mounted to rotate with said first mentioned handle, a plurality of pawls carried by said second handle and arranged to normally coact with said teeth for normally preventing the unseating of said valve stem, and means for 80 shifting said pawls out of coaction with said teeth.
3. A valve, comprising a body having a passageway therethrough, a valve stem, a 85 handle on said stem, coacting means on said body and stem adapted to shift said stem from one to the other of its limiting positions, a plurality of ratchet teeth on said body, a second handle slidably mounted on 90 said stem to rotate with said first mentioned handle, and a plurality of springs carried by said second handle and arranged to normally coact with said teeth for normally preventing the shifting of said stem toward 95 one of its limiting positions, said springs being shifted out of coaction with said teeth when said second handle is moved axially on said stem.
4. A valve, comprising a body having a 100 passageway therethrough, a valve stem, a handle on said stem, coacting means on said body and stem adapted to shift said stem from one to the other of its limiting positions, a plurality of ratchet teeth on said body, a second handle slidably mounted on 105 said stem to rotate with said first mentioned handle, yielding means normally urging said second handle to one position, and a plurality of springs carried by said 110 second handle and arranged to normally coact with said teeth for normally preventing the shifting of said stem toward one of its limiting positions, said springs being shifted out of coaction with said teeth when 115 said second handle is moved to another position.
5. The combination of a supply pipe, a valve comprising a body having a passageway therethrough, a valve stem, a lever handle on said stem, coacting means on said body and stem adapted to shift said stem axially from one to the other of its limiting positions by a substantially ninety degree rotation of said lever handle, a yoke 120 embracing a portion of said valve, a plate arranged to bear between said pipe and valve body, and means for causing tension be-

tween said yoke and plate for preventing said valve from shifting relative to said pipe when said lever handle is rotated.

6. A valve, comprising a body having a passageway therethrough, a valve stem, a handle for rotating said stem and slidable axially thereon, and ratchet means acting between said body and handle for normally

preventing the shifting of said stem toward one of its limits, said ratchet means being 10 retractable by the axial shifting of said handle.

Signed at Chicago this 12th day of Aug., 1915.

ANDREW STENGER.
